UNITED STATES PATENT OFFICE

ERNEST B. MILLER, OF BALTIMORE, MARYLAND

ADSORPTION SYSTEM

Application filed February 4, 1930. Serial No. 425,883.

This invention relates to air conditioning apparatus and methods, and more particularly to apparatus for dehumidifying or stripping air or gases in large quantities and continuously.

It is a general object of the present invention to provide novel methods and apparatus for continuously dehumidifying or stripping and tempering air or gases.

10 Among the features of novelty in this invention may be particularly enumerated the following:

(A) The use of several stages of adsorption arranged in the order of their saturation 11 for the removal of undesired constituents from air or gases.

(B) The passage of air or gases over a plurality of batches of adsorbent, together with the cooling of the fluid in its passage between 20 at least two of the batches.

(C) An arrangement whereby stripped air or gases delivered from adsorbers is mixed with a proportion of untreated air or gases and the ratio determined by the degree of saturation of the adsorbers.

(D) The use of a plurality of adsorbers whereby at least two are in the stripping circuit, one in an activating circuit, and one in a cooling circuit.

25 (E) The use of a closed fluid circuit provided with cooling means for removing the heat of activation from activated adsorbent.

(F) The use of a plurality of adsorbers in gas treating apparatus wherein each adsorber is provided with as many inlet ducts as there are adsorbers, and with a like number of outlet ducts.

(G) The arrangement of automatic damper controlling mechanism for instantly shifting each adsorber to a different phase in the process.

(H) An arrangement for activating saturated adsorbent by passing over it combustion gases diluted with a portion of such gases which have already passed over the adsorbent and with or without the addition of untreated air.

(I) The arrangement of adsorbent within an adsorbing chamber, together with inlet and outlet ducts so positioned as to give a

maximum exposure of the adsorbent to fluids passed from an inlet to an outlet duct.

While the most important objects and features of the invention have been enumerated above, it will be apparent to those skilled in the art, upon a consideration of the accompanying drawings and following specification, that various other objects and features are involved and will be claimed. The invention is disclosed, for the sake of convenience, in several embodiments, each adapted for a particular use, but it is to be understood that these embodiments are in no sense limited to the uses for which they are disclosed, and that the invention may be practiced in a number of ways which fall within the scope of the claims.

In said drawings;

Figure 1 is a diagrammatic and schematic showing of a simple form of the invention as used for drying the air for blast furnaces;

Figure 2 is a view similar to Figure 1 showing the apparatus arranged for conditioning air in a building or the like;

Figure 3 is a diagrammatic and schematic view of the arrangement of the actual air drying apparatus and accessories, wherein three adsorbers are used;

Figure 4 is a complete diagrammatic showing of a four-adsorber arrangement showing not only the accessories for treating the air, but the apparatus for controlling the valves in the inlet and outlet ducts and for activating the adsorbent; and

Figure 5 is a longitudinal section through one of the damper controlling valves of Figure 4.

Although the invention is explained for convenience, in connection with air dehumidifying and tempering systems it should be understood that the methods and apparatus are susceptible to use for stripping various constituents from gases.

It has heretofore been proposed to remove more or less of the moisture from atmospheric air by various processes, foremost among which may be mentioned refrigeration and adsorption in agents such as calcium chloride and the like. These various processes of moisture removal have not been

wholly successful, where practiced on a large scale, either due to the excessive cost of plant and operation, or because of the radical changes in temperature which are sometimes imparted to the air, requiring further expense to bring the air to the required temperature. Likewise the apparatus becomes bulky, expensive and requires too much manual attention. The present invention departs from the well known methods of drying air and provides a method which is so eminently satisfactory and so cheap to operate that it has already been widely adopted for drying the enormous quantity of air used in blast furnaces.

The method is a simple one and involves the adsorption of the moisture by bringing about an intimate contact between the air and one or more batches of adsorbent material. While a large number of adsorbents are satisfactory for use it is preferred, and the present invention is described as using silica gel of the type manufactured by The Silica Gel Corporation of Baltimore.

The invention as previously mentioned is susceptible to a large number of uses, but two of which are illustrated here.

Referring now to the drawings for a better understanding of the invention, Figure 1 shows an elementary form of apparatus for drying the air for a blast furnace. Air enters the duct 10 under the suction of the wind engine, not shown, and passes through the air filter 11 into the duct 12 which has a branch 13 leading to a suitable adsorber, generally indicated by the reference character 14 but which is in reality a more complex apparatus such as shown in Figures 3 and 4. In this adsorber a large portion of the moisture is adsorbed from the atmospheric air. Leaving the adsorber the air passes into the duct 15 and thence into the aftercooler 16 which reduces the temperature of the air which has been elevated due to the heat of adsorption. Thence the air passes into the duct 17 which is joined at 18 by the branch 19 leading off from the duct 12 ahead of the adsorber so that treated and untreated air meet at 18 and combine for delivery from the duct 20 leading to the wind engine.

The adsorber contains a suitable porous adsorbent such, for instance, as silica gel previously mentioned, and as this material becomes more and more saturated with the moisture abstracted from the atmosphere its rate of adsorption decrease. It is extremely important in blast furnace operation to maintain a substantially constant moisture content of the air delivered to the tuyères. This is more important than to have the minimum moisture content for it permits operation of the furnace to give a uniform output. Since the rate of adsorption of the adsorbent is not uniform some means must be provided to permit delivery of air of a uniform mois-

ture content and this is done by mixing the delivered dehumidified air with varying ratios of untreated air. Thus when the adsorber is acting at maximum capacity more air is passed through the by-pass 19 than passes through this same by-pass when the adsorber is acting at a minimum capacity, thus always maintaining a substantially constant delivery of air from the pipe 20. This regulation can be readily effected by having the dampers 21 and 22 in the ducts 19 and 17 respectively so interconnected that as one opens the other closes. These dampers can be automatically operated, for instance, by means of a hygrostat 23 in the outlet duct 20 so that the dampers are always set to give a uniform moisture content to the delivered air, which content is very much lower than that of the normal atmosphere. It will be appreciated that to maintain this constant humidity at the output irrespective of the humidity of the atmosphere the adsorber must have a capacity sufficient to remove the greater part of the moisture from air on even the dampest day.

The use of a cooler such as the after-cooler 16 is optional in the system and depends to some extent on the type of wind engine used. It may be placed ahead of the adsorber where it will increase the efficiency of adsorption which decreases as the temperature rises, or, it may be placed after the adsorber to reduce the temperature and thus the volume of air necessary to be handled by the wind engines. At 24 is indicated a group of accessories for the operation of the adsorber and they may include means for activating the adsorbent when it becomes saturated and other features which will be described in connection with the Figures 3 and 4.

Figure 2 shows in an elementary form a device for conditioning the atmosphere in a closed room or space where attention is directed mainly to the maximum dryness of the atmosphere rather than to any other conditions. This space, indicated by the reference character 25, is assumed to be substantially tight and is provided with an inlet or air delivery duct 26 and an outlet or air discharge duct 27. If the space is surrounded by walls which are substantially air tight, a suitable exhaust duct must be provided but under ordinary conditions there is sufficient leakage around windows and entries to permit a large loss of atmosphere especially if the plenum system is used.

Air from the atmosphere is drawn through the duct 28 into the filter 29 where dust is removed from it so that it will not clog the pores of the adsorbent. It is delivered into the duct 30 which leads into the precooler 31 where the air temperature is lowered before the air is delivered, by means of the duct 32, into the adsorber 33 of the type described in connection with Figure 1. From this adsorber it is delivered to the suc-

tion fan 34 which acts to draw the air through the adsorber where there is some little friction. From the fan 34 air is delivered by the duct 35 to the circulating fan 36 and thence to the duct 37, the main cooler 38 and into the duct 26 for delivery into the space 25 where it may be distributed at a plurality of points as 39. The adsorption fan also draws a certain amount of air from the exhaust duct 27 which takes in air from a plurality of points 40 within the space 25; through the main filter 41; the duct 42 and into the duct 30 where it combines with the fresh air and takes the course just described. The circulating fan may also draw a certain quantity of the air passing through the main filter 41 and the duct 43 which enters the duct 35 between the fans 34 and 36.

The system just described does not continuously deliver the full quantity of dried fresh air to the space 25, but delivers a portion of dried fresh air, a portion of dried return air and a portion of return air which is merely cooled. This reduces operating costs, for, under ordinary circumstances the air in the space 25 is not rapidly humidified and therefore is satisfactory for reuse if a portion of it is dried and mixed with some dried fresh air and returned. The function of the precooler is not only to cool the incoming fresh air but some of the air passing through the main filter which may have been heated in the space 25. It likewise contributes to the efficiency of adsorption. The main cooler removes the heat of adsorption and heat in the direct return air and permits the air to be delivered to the conditioned space at any temperature desired. These coolers as well as that shown in Figure 1 may be satisfactorily water cooled and are in effect large surface exchanges in which the water flows through a series of pipes in the air passages. Water is ordinarily available at temperatures below 70° so that the air can be cooled to a point satisfactory for use in buildings. A great many chemical operations can be best carried out at certain substantially fixed humidities and this apparatus is particularly adapted for that purpose. No automatic control of humidity is shown but it can readily be constructed to operate substantially like that shown in Figure 1. The total amount of fresh air can be controlled by the damper 44 in the duct 30. The dampers 45 and 46 control the amount of treated air; damper 47 controls the amount of return untreated air and damper 48 controls the total amount of air circulated.

Figure 3 shows in diagrammatic form an adsorber arrangement and particularly a system employing three adsorbers which have been marked #1, #2, and #3 for purposes of identification. The three adsorbers are identical and each comprises a large chamber preferably of sheet metal in which

the adsorbent is arranged in one or more layers or beds between reticulated supports in such a manner as to form a partition between opposite sides of the casing which are provided with inlet and outlet ducts. Thus any fluid entering one of the inlet ducts into the adsorber must pass through the layer or bed of adsorbent to reach an outlet duct. The particular arrangement of the adsorbent forms no part of the present invention. However, in accordance with the present invention it is found best to provide the same number of inlet ducts and the same number of outlet ducts as there are adsorbers in the system and the reasons will appear as the description proceeds.

Each adsorber in the embodiment of Figure 3, then has three inlet ducts *a*, *b*, and *c* which as shown are at the bottom of the drawings, and a like number and similarly lettered outlet ducts *a*, *b*, and *c*. In the description following it will be considered that when a fluid enters a duct it leaves by the correspondingly lettered duct which, however, is not directly opposite the entrance duct in order that the longest pass possible may be had through the adsorber. Each of the ducts, both inlet and outlet, is provided with a suitable valve to close off the duct and these valves are indicated in the conventional manner and will be referred to by the letters applying to the ducts. It is to be noted that the letters on the ducts of the various adsorbers are not arranged in the same positions with respect to these adsorbers and this is for the purpose of permitting the description to proceed regularly and to be simplified, for at any one time there is but a single inlet duct and its corresponding outlet duct open in each adsorber and if these are all of the same letter the operation will be more readily understood.

Air to be dehumidified enters the system through the duct 50, is filtered at 51, and delivered to the duct 52 which is continued in the form of manifold 53 which has three branch conduits 54, 55, and 56 leading respectively to the inlet ducts *c*, *a*, and *b* of adsorbers #1, #2, and #3. In the present instance it is considered that all of the *a* ducts have their valves open and that all of the remaining ducts in the adsorbers have their valves closed. Air therefore passes through the conduit 55, through the duct *a* into adsorber #2 and from exhaust duct *a* of that adsorber through conduit 57 into the manifold 58 which is connected also to the conduits 59 and 60 leading to the *c* and *b* outlet ducts of adsorbers #1 and #3 respectively. From this manifold 58 the air which has been partially dried in adsorber #2, enters the intercooler 61 where the heat of adsorption is removed from it, and it then enters the manifold 62 and follows that manifold to the conduit 63 which enters the *a*

inlet of adsorber #3. Passing through this adsorber the now thoroughly dried air leaves by the *a* outlet and enters the manifold 64 which is likewise connected to the *b* and *c* outlets of adsorbers #1 and #2 respectively. This manifold 64 delivers the air to the after-cooler 65 which delivers it to the conduit 66 leading to the fan 67 which is instrumental in circulating the air, from whence it is delivered through the conduit 68 for the use desired.

The by-pass conduit 69 leads from the inlet conduit 52 to the conduit 66 and performs the same function as the by-pass 19 in Figure 1. A damper is shown at 70 in the by-pass conduit and another at 71 in the outlet conduit 66, and these may be regulated to control the degree of humidity of the discharged air.

Adsorber #1 which was not involved in the passage of air for adsorption purposes, in the circuit just described, is assumed to have been saturated previously and is thus on the activating phase of the cycle. For the purpose of driving off the adsorbed moisture, heated combustion gases are forced through this adsorber to drive out the moisture. These gases are conveniently formed by burning any suitable fuel such, for instance, as city gas, blast furnace gas, or, the like in the furnace 72. The products of combustion with or without the addition of fresh air are conducted by means of the conduit 73 into the manifold 74. They are delivered into adsorber #1 through its *a* inlet and at proper times can be delivered into adsorbers #2 and #3 through their *b* and *c* inlets respectively. On passage through the adsorber, moisture is taken up by the heated gases which are delivered from the *a* outlet of adsorber #1 to the manifold 75 and thence to the fan 76 which causes their circulation, after which they are delivered into a suitable stack or other means for disposing of them, a suitable damper 77 being provided to regulate the rate of flow of these gases.

Adsorber #2 which first receives the air to be treated, in the phase of the cycle just described, is the more nearly saturated of the two on adsorption so that the gas passing through adsorber #3 which is least saturated has the last traces of its moisture removed with certainty. When adsorber #2 becomes saturated each of the three adsorbers is shifted in the circuits so that adsorber #3 first receives the air to be treated, adsorber #1 which has just been activated and hence has the least amount of moisture content is used as the "clean up" adsorber at the last passage of the air and adsorber #2 is placed on the activating phase. This is all accomplished by simultaneously closing all of the *a* valves and opening all of the *b* valves. This then will shift the position of each adsorber in the circuits as just described

and the cycle will be continued as previously. At each shift of the valves, each adsorber moves one step or phase in the cycle, thus each adsorber in succession is last in the adsorption phase, is then first in the adsorption phase and finally is on the activating phase. It might be thought that a heated adsorber just from the activating phase would not take up moisture but the outer layers of the adsorbent are almost instantly cooled by the cool air from the intercooler so that the small amount of moisture remaining in the air is readily taken up.

The aftercooler can be omitted if necessary but it is highly desirable to always use the intercooler. Of course a precooler can be added if required.

The aftercooler is used to bring the temperature of the treated air to the desired degree. Since the temperature of the air leaving the last adsorber in the cycle will be very high at the beginning, owing to the adsorbent having been just heated during activation, this air entering the aftercooler will require more cooling than at later stages of the adsorption. The temperature of the emitted air will fall rapidly during the first few minutes and to maintain a substantially constant output temperature it is desirable to have a thermostat in the air outlet of the aftercooler as at 78 and to have this connected to a diaphragm valve 79 in the inlet water line 80 of the aftercooler so that as the outlet air temperature tends to fall, the water supply to the cooler will be decreased, thereby maintaining a constant temperature out of the aftercooler.

In Figure 4 is shown a four adsorber plant and here it may be mentioned that any number of adsorbers may be used, each increase in the number adding to the adsorbers which are on the adsorption phase or as in the present instance permitting one of the adsorbers to be on a cooling phase after activation. It may better be stated that any number of adsorbers above four adds to the number on the adsorption phase since the cooling phase is desirable. The arrangement of the apparatus of Figure 4 is substantially identical, as regards piping, as that of Figure 3 and the whole description will therefore not be repeated. Each adsorber is seen to have one more inlet and one more outlet and there is one more manifold on the inlet side and another on the outlet side for connection to these additional inlet and outlet ducts.

The untreated air inlet is shown at 100 as including a filter, from whence the air is delivered to the conduit 101 and the manifold 102. With the assumption that all of the *a* valves are open the air is delivered to adsorber #2 for partial drying and from that adsorber is delivered to the manifold 103 which leads to the intercooler 104, from which the air passes to the adsorption fan 105, thence is

delivered into the manifold 106, from thence into the *a* inlet of adsorber #3 for further drying. It is then delivered into the manifold 107 leading to the aftercooler 108 from which it is delivered for use by means of the conduit 109, after being mixed, if desired, with fresh or untreated air from the by-pass 110, controlled by the valve 111. For the purpose of activating, air enters the filter 112 from whence primary air is delivered to the fan 113 which blows into the burner 114 supplied with suitable fuel and the mixture is delivered by the pipe 115 into the furnace 116 where secondary air is delivered from filter 112 by means of the pipe 117. From the furnace 116 the products of combustion pass through the filter 118 to remove any particles and are delivered to the pipe 119 leading to the manifold 120 which delivers the filtered products of combustion into the *a* inlet of adsorber #1 and from thence to the manifold 121; into the pipe 122 and to the activating fan 123 which serves to circulate these hot gases. From the fan a portion of the hot gases returned from the adsorber is delivered by the pipe 124 to the stack 125 and another portion is delivered into pipe 126 which joints the pipe 119 so that some of the heated gases are recirculated without passing through the furnace. Suitable dampers, as shown, control the proportion exhausted to the stack and delivered to pipe 126. At 127 is shown a damper controlled pipe which permits the products of combustion of the furnace to be delivered up the stack. This is particularly useful at starting when smoke is apt to be formed.

The remaining adsorber #4 is assumed to have just finished activating and is very hot. It is therefore connected in circuit with the gel cooler 130 from which air is drawn through the conduit 131 by the fan 132 and delivered into the manifold 133. This air, cooled by the water flowing through the cooler, passes through adsorber #4, is delivered through manifold 134 and pipe 135, and returned in a closed circuit to the gel cooler. In other words, air is merely circulated from the heated adsorber, through the gel cooler in a closed circuit. In this way there is no moisture added to the amount that the initial quantity of the air carries so that the adsorbent is not saturated during the cooling process.

When the valves are operated to close all of the *a* valves and open all of the *b* valves, each adsorber, as in the previous instance, moves in effect one position forward in the cycle so that the most saturated one is put on activation, the one just activated is put on cooling, and the one having been on second stage adsorption is placed in first stage. In order to operate the dampers or valves controlling the inlet and outlet ducts to the adsorbers each is provided with an operating

cylinder such as 140. These cylinders are in the form of the conventional cylinder of a steam engine and are provided with pistons for operating the valves or dampers, which when at one end of their stroke close the valves and at the other open the valves. It is preferred to use compressed air for operating the pistons and it will be seen that each cylinder is provided with a pair of pipes 141, one connected to the head end and the other to the rod end thereof. The head end pipes for all of the *a* valves are connected to distributor pipe 142 and the piston end pipes of the *a* valves to the distributor pipe 143 and those of the remaining valves likewise are connected to their respective distributor pipes. A source of compressed air, including the motor driven compressor 144 and the reservoir tank 145, is connected by a pipe 146 to valves 147, 148, 149, and 150, each also lettered *a*, *b*, *c*, and *d* to indicate their relation to the groups of adsorber duct valves which they respectively control.

Figure 5 shows in detail, in section, one of these valves. It is really a conventional D valve of the type used on steam engines and the pipe 146 supplies the chamber 152 with compressed air which is delivered from the port 153 when the valve is in the position shown, while the port 154 is connected to the exhaust passage 155. The D valve 156 is slideable so that it can open the port 154 to the compressed air and associate the port 153 with the exhaust. The valve is normally held in the position shown in Figure 5 by means of the spring 157 acting on its stem. The stem protrudes as at 158 through the other end of the casing 152 and there is connected by means of a centrally pivoted lever 159 to a roller 160 operating on a cam 161.

In Figure 4, four cams are shown on the shaft 162 each with a lobe of substantially 90° extent and with the lobes positioned respectively in the four quadrants. This provides that but one of the valves 147, 148, 149, 150 is open against its spring, at any one time and in Figure 4 the upper valve controlling the *a* valves of the adsorbers is shown open, that is, permitting air to be delivered to the ends of the cylinders 140 which causes opening of the *a* valves. All of the remaining valves 148, 149, 150 are so held by their springs that the *b*, *c*, and *d* valves of the adsorbers are closed.

The shaft 162 is driven by any suitable timing mechanism 163 which will give it a quarter turn at definite intervals preferably timed by the average length of time necessary to saturate an adsorber since activation can be performed in this time or less if necessary.

It can be seen from a comparison of Figures 3 and 4 that as the number of adsorbers increases the number of inlets and outlets to each adsorber increases correspondingly, to take care of the additional manifolds leading

to the adsorber, and the number of inlets and hence the number of outlets always corresponds to the number of adsorbers. If more than four adsorbers are used, say five, three will be in series on the adsorption phase and an additional intercooler is preferably provided so that the gas is cooled before its passage into each of the second and third adsorbers. With more than four adsorber units the control shown in Figure 4 would have additional cam operated valves, one for each additional adsorber but otherwise the construction would be substantially identical.

The arrangement of the adsorbers so that the adsorption takes place in stages is of particular advantage, for the moisture upon being adsorbed gives up its latent heat thereby increasing the temperature of the adsorbent and the air, and decreasing the adsorbent qualities of the material. By arrangement in stages provision can be made for intercoolers between stages to keep the temperature of the air lower. Second, the air partially dried by the first stages is lastly passed through an adsorber which has just been activated and hence is at the height of its capacity so that it easily removes the last remaining traces of moisture.

Having thus described the invention what is claimed as new and desired to be secured by Letters Patent is:

1. Apparatus for drying air comprising, in combination, a plurality of adsorbers each containing an adsorbent, means to connect at least two of said adsorbers in circuit with air circulating means to dry the air, a source of heated gas to revivify saturated adsorbent, means to place another adsorber in circuit with said source of heated gas and a circulating means, an air cooler in circuit between the two adsorbers on the adsorption phase, and valve means to periodically and automatically rearrange the adsorbers in the circuits to remove the most saturated one from the drying circuit to the revivifying circuit, said means inserting a fresh adsorber in the drying circuit and moving another from one side to the other of the cooler.

2. Apparatus for drying air comprising in combination, a plurality of adsorber housings each containing a quantity of adsorbent, each housing having as many inlets as the number of housings and a like number of outlets, a separate conduit for each set of corresponding inlets, a separate conduit for each set of corresponding outlets, valves between each conduit and its associated inlets or outlets, one of said inlet conduits being permanently connected to a source of air to be dried, one permanently connected to an air cooler and one permanently connected to a source of heated activating gas, said valves being so arranged that but one housing at a time can be connected to any one inlet and outlet conduit.

3. Apparatus for drying air comprising in

combination, a plurality of adsorber housings each containing a quantity of adsorbent, each housing having as many inlets as the number of housings and a like number of outlets, a separate conduit for each set of corresponding inlets, a separate conduit for each set of corresponding outlets, valves between each conduit and its associated inlets or outlets, one of said inlet conduits being permanently connected to a source of air to be dried, one permanently connected to an air cooler and one permanently connected to a source of heated activating gas, one of said outlet conduits being permanently connected to deliver the treated air, one being permanently connected to said cooler and one permanently connected to eduction means for said heated gas, said valves being so arranged that but one housing at a time can be connected to any one inlet and outlet conduit.

4. Apparatus for drying air comprising in combination, a plurality of adsorber housings each containing a quantity of adsorbent, each housing having as many inlets as the number of housings and a like number of outlets, a separate conduit for each set of corresponding inlets, a separate conduit for each set of corresponding outlets, valves between each conduit and its associated inlets or outlets, one of said inlet conduits being connected to a source of air to be dried, one to an air cooler and one to a source of heated activating gas, one of said outlet conduits being connected to said cooler and one to eduction means for said heated gas, said valves being so arranged that but one housing at a time can be connected to any one inlet and outlet conduit and means to periodically actuate said valves to change the connection of each adsorber housing to the conduits.

5. Apparatus for drying air comprising in combination, a plurality of adsorber housings each containing a quantity of adsorbent, each housing having as many inlets as the number of housings and a like number of outlets, a separate conduit for each set of corresponding inlets, a separate conduit for each set of corresponding outlets, valves between each conduit and its associated inlets or outlets, one of said inlet conduits being connected to a source of air to be dried, one to a dried air cooler, one to a source of heated activating gas and one to an adsorbent cooler, one of said outlet conduits being connected to deliver the treated air, one being connected to said dried air cooler, one to eduction means for said activating gas and one to said adsorbent cooler, said valves having operating means to periodically connect the adsorber housings each to one of the inlet conduits only and one of the outlet conduits only following a predetermined order.

6. An adsorber casing having a plurality of inlets at one side thereof and a like number of outlets at the other side thereof, valves for

said outlets and inlets, means controlling the opening and closing of said valves whereby but one inlet and one outlet is open at any one time, said controlling means being arranged to so open the valves that a cooperating inlet and outlet are never opposite each other whereby the gas takes a path through the casing longer than the shortest distance between the said sides.

10 7. Apparatus for drying air comprising, in combination, a plurality of adsorber housings each containing a quantity of adsorbent, each housing having as many inlets as the number of housings and a like number of outlets, 15 a separate conduit for each set of corresponding inlets, a separate conduit for each set of corresponding outlets, a valve between each conduit and its associated inlet or outlet, and means to periodically open one inlet valve and 20 its corresponding outlet valve for each casing and to simultaneously close all of the other valves for said casing.

In testimony whereof I hereunto affix my signature.
